UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed January 16, 1926. Serial No. 16,138. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein—

The dress is distinguished by the provision of a tunic having a flared lower end, the tunic being provided with a series of parallel lines of stitching presenting ornamental stripes extending vertically in parallel relationship and with a series of parallel lines of stitching presenting ornamental zigzag stripes or bands near the bottom

extending circumferentially, said stripes being of a color contrasting with the color of the tunic.

Figure 1 is a front view of a dress, showing my new design, the same being illustrated on a figure.

Figure 2 is a rear view of the dress shown in Figure 1.

Figure 3 is an enlarged fragmentary view of part of the lower end of the tunic, said view illustrating the ornamental arrangement of the stitching forming the vertical and circumferential stripes.

I claim:

The ornamental design for a dress, substantially as shown and described.

TAUBE DAVIS.
